UNITED STATES PATENT OFFICE.

HERMAN C. PRIEBE, OF BLUE ISLAND, ILLINOIS.

DRAFT-GEAR.

1,208,650.

Specification of Letters Patent. Patented Dec. 12, 1916.

Original application filed August 27, 1914, Serial No. 858,854. Divided and this application filed March 8, 1915. Serial No. 12,724.

To all whom it may concern:

Be it known that I, HERMAN C. PRIEBE, a citizen of the United States, residing at Blue Island, in the county of Cook and State of Illinois, have invented a certain new and useful Improvement in Draft-Gears, of which the following is a full, clear, concise, and exact description, reference being had to the accompanying drawings, forming a part of this specification.

My invention relates to draft gears employed in the construction of railroad cars, the present application being a division of my original application Serial No. 858,854, filed August 27, 1914.

The spring portions of my improved draft gear are of such formation as to enable the employment of more spring mechanism in a given space than hitherto.

I will explain my invention more fully by reference to the accompanying drawing showing the preferred embodiment thereof and in which—

Figure 1 is a longitudinal sectional elevation of a portion of a car structure illustrating a draft gear that includes one form of the invention; Fig. 2 is a view on line 2 2 of Fig. 1; and Fig. 3 is a view on line 3 3 of Fig. 1.

Like parts are indicated by similar characters of reference throughout the different figures.

The outer ends of the draft arms 11, 12 are arranged to support the draft rigging, the type of draft rigging illustrated including some features of construction which are set forth and claimed in my co-pending application Serial No. 800,442, filed November 12, 1913. Each draft rigging is shown as including a coupler shank 28 whose inner end is provided with pockets which receive the short sides of hooks 29 in which a coupler yoke 30 terminates, as set forth in my co-pending application. Keys 31 extend transversely through the draft arms and are rigid with respect to followers 32, 33 through which these keys also pass, the front follower 32 being engaged by the inner end of the coupler shank while the rear or inner follower 33 is engaged by the inner end of the yoke 30. The slots 34 through which the keys 31 pass are longer than the width of the keys so that each key is capable of bodily movement longitudinally of the car. Spring

carriers 35 are provided with slots 36 co-extensive in length and aligned with the slots 34. Coil springs 37 surround the portions of the carriers 35 that intervene between the keys 31. Two sets of coil springs 38 intervene between the followers 32 and 33 which are provided with insetting lugs 39 that enter the bores of the springs 38 to position the same. The keys 31, by passing through the elongated slots 34, not only take part in supporting the followers and the springs which tend to force the followers apart but also have supporting engagement with the draft arms that also thus constitute draft gear carrier irons. The draft gear carrying function of the draft arms is supplemented by the plate 40 which is bolted beneath the coupler shanks that bear upon these plates as the shanks are moved in and out and are oscillated.

I increase the capacity of the springs that are operatively interposed between the followers 32 and 33 and, reduce the lateral dimensions of the space occupied by these springs by making the bores of the springs elliptical with the major axes of the bores of the outer springs 37 vertically disposed. I am thus enabled to interpose two springs between each pair of draft arms which together are of greater capacity than any single spring could be which has a cylindrical bore, for a given length of spring, and while the inner springs 38 preferably have the major axes of their bores upright I do not wish to be limited to this arrangement. The bores of the outer springs 37 should have their major axes upright in order to enable me to increase the capacity of these springs for a given length of the keys 31. The bending moments exerted thereupon by the springs having elliptical bores would be less than the bending moments of cylindrical springs of similar capacity since the springs having elliptical bores exert their pressure upon the keys at more closely approximated points than would the cylindrical springs. I have illustrated one peculiar arrangement by which the spring capacity may be increased by making the bores of coil springs elliptical in order to dispose these springs in space of peculiar limitations. It is obvious that the spring feature of my invention may be employed where other spacing limitations are encountered in connection with which

springs having elliptical bores could be used to secure an increase of spring capacity that could not be obtained with the cylindrical springs hitherto employed. The outer 5 springs 37, by being constructed as illustrated most clearly in Fig. 3, enable me to make the keys 31 shorter and in order that these springs may underlie the center sills as closely as possible the outer edges of the 10 wings 19 are upwardly deflected and set into the center sills 2 as indicated in Fig. 3.

While I have herein shown and particularly described the preferred embodiment of my invention I do not wish to be limited to 15 the precise details of construction shown as changes may be readily made without departing from the spirit of my invention, but

Having thus described my invention I claim as new and desire to secure by Letters 20 Patent the following:—

1. A draft gear including the followers thereof; a yoke structure coöperating with the followers; and a pair of coil springs located side by side between the sides of the 25 yoke structure and interposed between these

followers, the bores of these coil springs being elliptical.

2. A draft gear including the followers thereof; a yoke structure coöperating with the followers; and a pair of coil springs located side by side between the sides of the yoke structure and interposed between these followers, the bores of these coil springs being elliptical, the major axes of these bores 30 being disposed upright. 35

3. A draft gear including the followers thereof; transversely extending keys movable longitudinally of the gear and engaging the followers; and coil springs interposed between said keys, the bores of the springs 40 being elliptical with the major axes of the bores upright.

In witness whereof, I hereunto subscribe my name this thirty-first day of October, A. D. 1914.

HERMAN C. PRIEBE.
